SPRAY NOZZLE

Fred S. Rosenthal, Chicago, Ill.

Application October 19, 1949, Serial No. 5,575

Term of patent 14 years

(Cl. D91—1)

To all whom it may concern:

Be it known that I, Fred S. Rosenthal, a citizen of the United States, residing at Chicago, in the county of Cook and State of Illinois, have invented a new, original, and ornamental Design for a Spray Nozzle, of which the following is a specification, reference being made to the accompanying drawing, forming a part hereof.

In the drawing:

Fig. 1 is an end elevational view of a spray nozzle embodying my new design;

Fig. 2 is a side elevational view; and

Fig. 3 is a transverse sectional view taken along the line 3—3 of Fig. 2.

I claim:

The ornamental design for a spray nozzle, substantially as shown.

FRED S. ROSENTHAL.
